UNITED STATES PATENT OFFICE.

PENDLETON S. CLARK, OF LYNCHBURG, VIRGINIA.

SAFETY-RAZOR-BLADE HOLDER.

Application filed October 30, 1928. Serial No. 316,059.

My invention relates to a holder for safety razor blades.

As is well known, used safety razor blades are frequently allowed to lie around a bathroom or the like. These blades are dangerous, particularly where there are young children.

I am aware of the fact that attempts have heretofore been made to provide receptacles 10 for receiving and holding these blades. These receptacles are usually formed of metal, and are so constructed that they project out beyond the wall, to which they are attached. They are accordingly in the way, to some extent, and are unsightly.

In accordance with my invention, I provide a safety razor blade holder which is preferably formed of tile, to match the tile in a bathroom, and the holder is set onto the wall, 20 so that its outer face is substantially flush with the outer face of the tile. The front wall has a slot or opening, for the passage of the blades, and a sliding drawer is mounted in the bottom of the receptacle or body portion 25 of the device, the outer face of the drawer being flush with the outer face of the body portion. A suitable knob or the like is employed to open and close the drawer, which may actuate a latch or lock. A separate lock 30 may be employed for the drawer, if desired.

In the accompanying drawings, forming a part of this specification, and in which like numerals are employed to designate like parts throughout the same,

Figure 1 is a perspective view of the safety razor blade holder embodying my invention,

Figure 2 is a front elevation of the same, and,

Figure 3 is a vertical section taken on line 40 3—3 of Figure 1.

In the drawings, wherein for the purpose of illustration, is shown a preferred embodiment of my invention, the numeral 5 designates the tile, set upon the wall of the bathroom or the like, an opening 6 being formed in the tile and wall.

The numeral 7 designates a box, receptacle, or body portion of the holder, preferably formed of porcelain or china, or of material 50 corresponding to the ordinary tile. This receptacle is preferably rectangular and has a flat front face 8, which preferably corresponds in appearance and color to the tile. The front face 8 is arranged substantially flush with the face of the tile. The numeral 9 designates an opening or slot for the in-

sertion of the safety razor blades, ordinarily used safety razor blades. These blades fall into a sliding drawer 10, arranged in the bottom of the receptacle 7 and movable through 60 a rectangular opening 11, formed in the front face 8. When the drawer 10 is closed, its front face 12 is substantially flush with the front face 8. The face 12 is provided with an opening 13, receiving a pivoted stem 14, carrying a knob 15. Secured to the rear end 65 of the stem 14 is a catch or latch 16, to engage behind the front face of wall 8, and to hold the drawer 10 in the closed position. If desired, a separate latch or lock may be employed to hold the drawer 10 in the closed 70 position. The box 7 is also shown as having a length substantially equal to the length of the complete tiles 5, and a height substantially equal to the combined height of two 75 of the tiles. The drawer 10 has a length and height corresponding generally to the length and height of a complete tile 5. The front face 12 of the drawer and the front face 8 of the box, therefore, have the general appearance of two tiles, whereby the general tile effect of the wall is not unduly disturbed.

In use, the safety razor blades are passed through the openings 9, and are caught in the drawer 10. When it is desired to empty 85 the drawer, it may be readily removed from within the receptacle or casing 7.

The holder having all parts, excepting the knob 15, substantially flush with the outer face of the tile, presents a pleasing and attractive appearance, and is also entirely out of the way. The device is preferably formed of a porcelain or tile, corresponding in appearance with the tile of the bathroom.

It is to be understood that the form of my 95 invention, herewith shown and described, is to be taken as a preferred example of the same, and that various changes in the shape, size and arrangement of parts may be resorted to without departing from the spirit 100 of my invention, or the scope of the subjoined claim:

Having thus described my invention, I claim:

A used safety razor blade holder adapted 105 to be mounted within a recess formed in a tiled wall, such recess extending through two layers of the tile, said holder comprising a rectangular box formed of porcelain and mounted within the recess with its outer face 110 substantially flush with the outer face of the tile, said box having substantially the same

length as a complete tile and a height substantially equal to the combined height of two tiles, the outer face of the box being provided in its lower portion with a rectangular drawer receiving opening which has the shape of a complete tile and generally the same size as the same, said outer face being provided in its upper portion with a contracted slot for the insertion of the used safety razor blades, and a rectangular porcelain drawer adapted to be slidably mounted

through the drawer receiving opening and having an outer face which is substantially flush with the outer face of the box when the drawer is closed, the outer face of the drawer and the upper outer face of the box resembling generally two superposed tiles, and means whereby the drawer may be shifted to opened and closed positions.

In testimony whereof I affix my signature.

PENDLETON S. CLARK.
